UNITED STATES PATENT OFFICE.

FRANK J. FREY, OF QUINCY, ILLINOIS, ASSIGNOR TO H. WETTER
MFG. CO., OF MEMPHIS, TENNESSEE.

DESIGN FOR A STOVE.

No. 38,083.

Specification for Design.

Patented June 12, 1906.

Application filed April 17, 1906. Serial No. 312,270. Term of patent 7 years.

To all whom it may concern:

Be it known that I, FRANK J. FREY, a citizen of the United States, residing at Quincy, in the county of Adams and State of Illinois, have invented a new, ornamental, and original Design for Stoves, of which the following is a specification.

The figure is a perspective view of a cooking-stove embodying my new design.

I claim—

The ornamental design for a stove, as shown.

FRANK J. FREY.
